UNITED STATES PATENT OFFICE.

ALVA L. PALMER, OF JAMAICA, NEW YORK.

COVER-REMOVING DEVICE FOR FURNACES.

1,390,581.

Specification of Letters Patent. Patented Sept. 13, 1921.

Application filed October 24, 1919. Serial No. 332,959.

To all whom it may concern:

Be it known that I, ALVA L. PALMER, a citizen of the United States, residing at Jamaica, (L. I.,) in the county of Queens 5 and State of New York, have invented certain and useful Improvements in Cover-Removing Devices for Furnaces, of which the following is a specification, reference being had therein to the accompanying drawing.

10 This invention relates to a crucible furnace or the like, and contemplates an improved form of mechanism for removing the top or cover of the furnace whenever desired.

15 According to one feature of the invention, the cover is pivotally connected to a supporting rod or carrier which is mounted for free rotation in a holder applied to the furnace, the arrangement being such that in removing the cover, it is first swung upwardly to a vertical position on the supporting rod or carrier and the latter then rotated in the holder to locate the inner heated face of the cover away from the operator.

20 25 According to another feature, the holder is so constructed and arranged as to be adjustable around the furnace to locate the supporting rod or carrier in any desired position about its circumference or perimeter.

30 35 According to still another feature, the holder is adjustable vertically on the furnace so as to raise or lower the supporting rod or carrier for one reason or another.

According to further features of the invention, the holder is constructed in the form of an attachment which may be readily applied to or removed from the furnace as a whole; which may be expanded or contracted at will to accommodate furnaces of different sizes; and which may be mounted and sustained on the furnace without drilling, riveting, welding or any other form of permanent fastening.

40 45 In addition the invention aims to provide a mechanism which, while capable of carrying out the above features, may be made and applied to the furnaces at little expense and which at the same time will be strong and durable and easily manipulated.

50 Referring to the drawing:

Figure 1 is a side elevation of a furnace equipped with the improved mechanism;

Fig. 2 is a similar view showing the furnace cover removed from closed or operative 55 position;

Fig. 3 is a top plan view taken on the line 3—3 of Fig. 1.

The improvements are herein illustrated in connection with the cylindrical crucible furnace 1 of the well known type, although 60 they are equally applicable to other kinds of furnaces or to furnaces of other shapes. As usual, the furnace is formed near its bottom with the opening or conduit 2 leading tangentially into the combustion chamber 65 and through which the flame from the burner 3 is forced under the action of the fan or blower 4. The furnace is closed at the top by the circular fire brick cover 5 formed with the central opening 6 through which 70 the products of combustion escape.

It is well known that in the use of such furnace, the cover cannot be easily manipulated, not only by reason of its weight but because it becomes intensely heated. The 75 present invention is therefore designed to provide an improved form of mechanism whereby the cover may be removed mechanically from the furnace and located with its inner heated face away from the operator. 80 Such mechanism will first be described in detail and the more important features later pointed out, it being understood that other forms of mechanism might readily be employed to carry out certain features of the 85 invention. As before stated, the improved devices consist essentially of a carrier for the cover, and a holder applied to the furnace and wherein the carrier is movably mounted.

As herein shown, the carrier is in the form 90 of a vertical rotatable supporting rod or post 7 provided with a three part hoop or band 8 which is pivotally connected to the supporting rod by means of a bolt 9 passing through a lug 10 thereon and joining the 95 adjacent ends of two of the band segments. At the other points, the segments are connected together by clamping bolts 11, which draw them together to tighten the band firmly about the cover. As a result of this 100 construction, the cover may be swung upwardly and downwardly on the supporting rod 7, turning about the bolt 9 as a pivot. To facilitate this pivotal movement of the 105 cover, the band 8 is formed with shackles or eye-pieces 12 adapted to receive a crowbar in the hands of a workman or hooks attached to some mechanical lifting means. In order to hold the cover in its raised or vertical position, the supporting rod 7 is provided at 110

the top with a spring latch 13 formed with a transverse notch or recess wherein a lip 14 on the band 8 is adapted to engage automatically.

- 5 In the present embodiment, the holder for the supporting rod or carrier is in the form of two segmental hoops or bands 15 fitted about the furnace and whose segments are connected together by clamping bolts 16.
- 10 which draw the bands tightly about the furnace and with sufficient pressure to enable them by their frictional engagement therewith to support the weight of the parts. The upper band is provided with a plain bearing sleeve or ring 17 through which the supporting rod 7 loosely passes; while the lower band is provided with a thrust bearing or socket member 18 upon which the lower end of the supporting rod rests, it being noted that the rod is reduced at its lower end and passes through a corresponding opening in the socket member. In this way, the free rotation without endwise movement of the supporting rod in the holder is provided for, although any other suitable form of bearings may be employed for the purpose.

It will now be clear as to how the various features before mentioned are realized.

30 In removing the furnace cover, it is first swung upwardly about the pivot 9 and locked in its raised or vertical position by the latch 13, and then the supporting rod 7 is rotated in the bearings 17 and 18 of the holder to locate the cover in any desired position, it being remembered that these bearings are such as to permit a free rotation of the supporting rod without endwise movement either to the left or right and throughout an angle of 360 degrees. This arrangement is therefore to be distinguished from a construction wherein the cover is first raised facewise in a horizontal position and then turned in its own plane to one side of the furnace, the essential idea in the present instance being to effect the removal of the cover first by swinging it upwardly and then turning it laterally to one side. Such a construction permits the closer arrangement of a series of furnaces than would otherwise be possible, not to mention other advantages arising therefrom.

The adjustment of the holder to alter the position of the supporting rod or carrier about the furnace is effected by shifting the bands 15 around the furnace until the supporting rod is located in the desired position, it being necessary merely to loosen and retighten the clamping bolts 16 before and after such shifting of the bands. This feature is very advantageous in that it allows the supporting rod to be set in any position with reference to the burner opening 2 which in practice is often required to face 65 in various directions to accommodate the

burner and fan attachment. To meet such a condition it has been a common practice to cut an additional opening in the furnace and to plug up the original opening. This objectionable procedure is obviated under 70 the present arrangement, which allows the supporting rod to be adjusted toward or from the burner opening as required. Similarly, when it is desired for any reason to raise or lower the supporting rod to locate 75 the cover band 8 nearer to or farther from the furnace, this may be done by loosening the clamping bolts 16 and slipping the holder bands 15 up or down on the furnace and then retightening the bolts to confine 80 the bands in the new position. In this way, for instance, any variation in the size or thickness of the cover may be provided for or any wear thereon taken up, although in the present embodiment some slight adjustment of the cover is allowed by reason of the use of the segmental band 8 which will permit the cover to be raised or lowered 85 within it.

The application of the parts to and their 90 removal from the furnace is made possible by the employment of the segmental bands 8 and 15, the latter providing for the mounting of the supporting rod or carrier on the furnace, and the former for the connection 95 of the supporting rod to the furnace cover. In other words, the parts are constructed in the form of an attachment which may be applied to any furnace or shifted from one to another at will. In fact, the attachment 100 may be employed to convert a furnace of one kind into one of a different variety. Thus, it is common practice to convert a furnace designed for the use of coal or coke into one for the use of gas or oil, this 105 conversion being brought about by removing the light cover employed when coal or coke is used and substituting therefor a heavy firebrick cover necessary in the use of gas or oil. The present attachment is peculiarly 110 adapted for such purpose, as the holder may be easily applied to the coal furnace and the supporting rod or carrier then connected by means of the band 8 to the heavy firebrick cover.

In addition to the feature last mentioned, the attachment is capable of being applied to furnaces of different sizes or diameter, this being permitted of course by the use of the split or segmental holder bands 15 120 which may be expanded or contracted by the loosening or tightening of the clamping bolts 16, as may be required. Likewise, the pivoted band 8 of the supporting rod or carrier may be fitted to covers of different diameter, 125 although these latter do not vary to the same extent as the furnace bodies.

It is further pointed out that the holder bands 15 (which are made of steel) furnish additional reinforcement for the firebrick 130

wall of the furnace, and might allow the usual sheet metal casing to be made thinner, if that were desired.

While designed primarily to carry out the various features outlined, it may be noted that the improved mechanism is extremely simple and comprises but few parts which can be made cheaply and easily fitted together without requiring any extensive machining or drilling operations such as characterize prior constructions and without involving any alteration whatever in the existing parts, which may therefore be manufactured in the usual way. These and various other advantages will be apparent to those skilled in the art.

In its broader aspects, the invention is not limited to the precise construction shown and described, as many changes may be made in the details thereof without departing from the spirit of the invention or sacrificing its chief advantages. Generally speaking, it is to be understood that the invention is not limited to any specific form of arrangement, excepting in so far as such limitations are specified in the claims.

Having thus described my invention, what I claim and desire to secure by Letters Patent, is as follows:

1. The combination with a furnace having a removable cover, of a rotatable supporting rod to which the cover is pivotally connected, and a holder attached to the furnace and wherein the supporting rod or carrier is freely rotatable without endwise movement; whereby in removing the cover, it is first swung upwardly on the supporting rod or carrier and the latter then rotated in the holder to locate the cover in any desired position.

2. The combination with a furnace having a removable cover, of a rotatable supporting rod or carrier to which the cover is pivotally connected and provided at the top with automatic locking means to engage and hold the cover in its raised position, and a holder attached to the furnace and wherein the supporting rod or carrier is freely rotatable without endwise movement.

3. The combination with a furnace having a removable cover, of a rotatable supporting rod or carrier to which the cover is pivotally connected, and a holder wherein the supporting rod or carrier is rotatably mounted without endwise movement; whereby in removing the cover, it is first swung upwardly on the supporting rod or carrier and the latter then rotated in the holder to locate the cover in any desired position.

4. The combination with a furnace having a removable cover, of a rotatable supporting rod or carrier to which the cover is pivotally connected, and a holder wherein said supporting rod or carrier is journaled, the said holder being attached to the furnace

and adjustable therearound to locate the supporting rod or carrier in different operative positions about the circumference or perimeter of the furnace, for the purpose described.

5. The combination with a furnace having a removable cover, of a rotatable supporting rod or carrier to which the cover is pivotally connected, and a holder wherein said supporting rod or carrier is journaled, the said holder being attached to the furnace and adjustable vertically thereon to raise or lower the supporting rod or carrier, for the purpose described.

6. The combination with a furnace having a removable cover, of a rotatable supporting rod or carrier to which the cover is pivotally connected, and a holder wherein said supporting rod or carrier is journaled, the said holder being frictionally attached to the furnace so as to be removable therefrom freely and at will.

7. The combination with a furnace having a removable cover, of a rotatable supporting rod or carrier to which the cover is pivotally connected, and a holder wherein said supporting rod or carrier is journaled; the said holder being in the form of segmental hoops or bands fitted about the furnace and having their segments connected together by clamping devices which draw the bands tightly about the furnace with sufficient pressure to enable them to sustain the weight of the parts.

8. The combination with a furnace having a removable cover, of a movable carrier to which the cover is connected, and a holder wherein said carrier is movably mounted and adjustable around the furnace to locate the carrier in different positions about the circumference or perimeter of the furnace.

9. The combination with a furnace having a removable cover, of a movable carrier to which the cover is connected, and a holder wherein the carrier is movably mounted, the said holder being attached to the furnace and adjustable around the same to locate the carrier in different operative positions about the circumference or perimeter of the furnace.

10. The combination with a furnace having a removable cover, of a movable carrier to which the cover is connected, and a holder wherein the carrier is movably mounted, the said holder being frictionally attached to the furnace so as to be removable therefrom freely and at will.

11. An attachment for furnaces comprising a movable carrier provided with means by which the cover of a furnace may be connected thereto, and a holder wherein the carrier is movably mounted, the said holder being in the form of hoops or bands adapted to be fitted about the furnace.

12. An attachment for furnaces comprising

ing a movable carrier provided with means by which the cover of a furnace may be connected thereto, and a holder wherein the carrier is movably mounted, the said holder 5 being in the form of segmental hoops or bands adapted to be fitted about the furnace and having their segments connected together by clamping devices which draw them together to tighten the bands about the 10 furnace when attached thereto.

13. An attachment for furnaces comprising a movable carrier provided with means by which the cover of a furnace may be connected thereto, and a holder wherein 15 the carrier is movably mounted, the said holder being in the form of hoops or bands adapted to be fitted about the furnace and formed in relatively adjustable segments or sections which may be expanded or contracted at will to correspond to the size of 20 the furnace to which the holder is applied.

14. An attachment for furnaces comprising a vertical supporting rod provided with a pivoted hoop or band adapted to be fitted 25 about the cover of a furnace, and a holder in the form of hoops or bands adapted to be fitted about the furnace and provided with bearings wherein the supporting rod is rotatably mounted.

30 15. An attachment for furnaces comprising a vertical supporting rod provided with

a pivoted hoop or band adapted to be fitted about the cover of a furnace, and a holder in the form of hoops or bands adapted to be fitted about the furnace and provided with 35 bearings wherein the supporting rod is rotatably mounted, both the cover band and the furnace bands being formed in sections or segments connected together by clamping bolts, for the purpose described. 40

16. An attachment for furnaces comprising a vertical supporting rod provided with a pivoted hoop or band adapted to be fitted about the cover of a furnace, and a holder having means by which it may be applied 45 to the furnace and formed with bearings wherein the supporting rod is rotatably mounted, the said supporting rod being provided near the top thereof with an automatic detent arranged to engage a part of 50 the cover band when the latter is swung upwardly on its pivot.

17. An attachment for furnaces comprising the vertical rod 7 provided with the pivoted band 8 and the detent 13, and the 55 holder bands 15 provided with the bearings 17 and 18 respectively, all in the manner and for the purpose described.

In testimony whereof, I have affixed my signature hereto.

ALVA L. PALMER.
